UNITED STATES PATENT OFFICE.

JOSEPH VAS DIAS, OF AMSTERDAM, NETHERLANDS.

SUSPENSION-BORDER FOR SHOW-CARDS, MAPS, ALMANACS, AND THE LIKE.

1,309,319.

Specification of Letters Patent.

Patented July 8, 1919.

Application filed December 19, 1917. Serial No. 207,962.

To all whom it may concern:

Be it known that I, JOSEPH VAS DIAS, lithographer and paper-manufacturer, subject of the Queen of the Netherlands, residing at Amsterdam, Kingdom of the Netherlands, have invented certain new and useful Improvements in Suspension-Borders for Show-Cards, Maps, Almanacs, and the like, of which the following is a specification.

10 The hanging up and keeping stretched of wall-pictures of any kind, such as posters, show-cards, maps, sheet-almanacs and the like, is done, as is known, by means of suspension-borders which, according to requirements, are either fixed alone to the top edge of the sheets as in the case of sheet-almanacs, or fixed on to the top as well as to the bottom edge, as in the case of advertising-posters, show-cards and maps.

20 These borders or frames must have sufficient strength to offer resistance against any deformation of the paper caused by atmospheric influence, and also must be sufficiently strong to avoid buckling or breaking; the bottom borders, especially, have to be heavy enough to keep pictures smooth and stretched while hanging or while being despatched in rolls.

30 The suspension borders most often hitherto used consist of a double folded strip of sheet-iron fixed on the top and on the bottom edge of the print, the two parts of which are pinched toward each other by pressure so as to form one half of a hollow suspension border and to keep the sheet to be hung up tight. This arrangement is such as to allow the convex side of the pressed border to come in sight.

When applied to wall-almanacs consisting 40 of several sheets, the suspension-border may be formed by the aid of a double sheet of thin cardboard of which a cloth-back is adjusted, which border is fixed on to or around the top-edge of the sheet-almanac. Borders 45 of this kind are not in raised relief being flat.

However, these well-known suspension-borders only answer partly the above stated requirements; in the first place for the reason that the high prices of sheet-metal form a 50 drawback to the use of sufficiently strong iron-sheets; secondly, because the use of suspension-borders made of strong sheet-metal impedes the bending and fixing of the metal-plate, and in addition to this, the use of borders made of thick iron plates does not improve their aspect.

On the other hand, the use of thin metal plates involves the risk of impairing the appearance of the sheets by the bending of the metal plates, due to the small resistance offered by them, or of the sheets being crumpled up and, frequently, even made unserviceable altogether. If, moreover, the bottom edge is not sufficiently heavy, the edge of the paper is liable to curl up which, of course, would be rather troublesome.

In consequence of these suspension-borders having to be fixed by stamps on the paper and the like, they always adopt the shape of the stamp or punch, while it would offer a neater aspect if the said borders would be given the shape or the character of a frieze in relief.

The object of my present invention is a suspension-border avoiding the above described drawbacks, and permitting the resistance as well as the weight and the contour of the said suspension-border to be regulated or altered according to requirement. Another characteristic feature being that 80 the attachment of said suspension border to the sheet can be effected without exercising mechanical pressure.

The suspension-border, according to the present invention, consists of one or more 85 cylindrical or semi-cylindrical or otherwise shaped tubes of rolled-up paper or of any other suitable fibrous material being shaped into rolls or tubes; the said tubes may be filled with some weight-increasing material 90 and the printed sheets are affixed to same.

The formation of the tubes can be effected in any suitable way. In manufacturing such tubes of paper or of some other fibrous matter such as linen, I have found it useful to 95 cover the said material with some adhesive substance, have this material rolled up in tubes and allow the adhesive substance to harden on the same.

To increase the weight of these tubes and 100 to enable same to keep the hung-up pictures, maps or the like, stretched and even, the tubes may be filled with some material of greater specific gravity such as concrete, sand, gypsum, iron-filings, lead-slacks, 105 stone-chips or the like.

In the accompanying drawing Figure 1 represents a cross-sectional view of a tubular suspension border embodying my invention, showing a part of the suspended article attached to the tab of the same; and

Fig. 2 represents a modification thereof.

The tubular roll is designated by *a* and may be either cylindrical in shape as shown in Fig. 1 or semi-cylindrical as shown in Fig. 2. Whatever the form of the roll it is made from a sheet of material which leaves an integral tab *c* depending from the roll for the attachment of the suspended article *b* by adhesive or other convenient fastening means. As shown in Fig. 2 a smaller tube 10 or roll *a'* may be interposed between said article and tab and attached adhesively to the latter the article *b* being similarly attached to said depending part *c'*.

These borders may be covered with fancy-15 paper.

I claim:

1. A suspension border for maps and other articles consisting of a roll of foldable non-metallic fibrous material, said roll being 20 formed from a sheet covered with adhesive material which hardens thereon but permits the adhesive attachment of the suspended article, said roll being also supplied inter-

nally with heavier material and having an unwound flat part of the said sheet for the 25 attachment of said article thereto.

2. A suspension border for maps and other articles consisting of a roll of foldable non-metallic fibrous material, said roll being 30 formed from a sheet covered with adhesive material which hardens thereon but permits the adhesive attachment of the suspended article, said roll being provided with a depending unwound flat part of the sheet for convenience of attaching said article. 35

3. A suspension border for maps and other articles consisting of a roll formed from a sheet of non-metallic material and provided with an unwound flat depending part for convenience of attaching such article. 40

In testimony whereof I have affixed my signature in presence of two witnesses.

JOSEPH VAS DIAS.
